UNITED STATES PATENT OFFICE.

LOUIS STEINBERGER, OF NEW YORK, N. Y.

TUBULAR INSULATOR.

No. 927,185.

Specification of Letters Patent.

Patented July 6, 1909.

Application filed June 4, 1906. Serial No. 320,068.

To all whom it may concern:

Be it known that I, LOUIS STEINBERGER, a citizen of the United States, and a resident of the city of New York, borough of Brooklyn, in the county of Kings and State of New York, have invented a new and Improved Tubular Insulator, of which the following is a full, clear, and exact description.

My invention relates to insulators, my more particular object being to produce a high-tension insulating tube suitable for insulating cables, wires and other conductors, energized by high-tension currents, the tube providing a very high degree of insulation and at the same time affording great mechanical strength.

Among the several objects I accomplish by my insulating tube are the following: 1, to provide an insulating tube having protected portions and drip edges on the outer surface, thereby reducing the surface leakage to a minimum; 2, to provide a tube of novel construction combining the use of solid material with air spaces; 3, to provide an insulating tube of such conformity as to economize the material for enabling air spaces to perform the office of insulation; 4, to provide an insulating tube that combines compactness, large housing area, a very high degree of insulation, and great mechanical strength; 5, to provide an insulating tube that will admit a comparatively large cable and at the same time provide a plurality of separate insulating compartments for the admission of smaller cables, wires, or other forms of conductors; 6, to provide an insulating tube of such novel construction that should a portion of the outer tube become damaged or broken through it will not injure the cable threaded through its central orifice; 7, to provide a tube of such novel conformity as to offer great resistance to both crushing and torsional strains.

Reference is to be had to the accompanying drawings forming a part of this specification, in which similar characters of reference indicate corresponding parts in all the figures.

Figure 1 is a side elevation of an insulating tube made in accordance with my invention; Fig. 2 is a substantially central section through a plurality of insulating tubes shown in Figs. 1 and 3, and connected together into a continuous member, the section being taken on the line 2-2 of Fig. 3; Fig. 3 is a horizontal section of the insulating tube and is taken upon the line 3-3 of Fig. 2,

looking toward the bottom of the sheet; and Fig. 4 is an end elevation of the insulating tube.

Tubular members 4, 5 and 6 are disposed concentrically, the innermost being provided with an annular cylindrical space 7 through which a cable or other conductor may be threaded. Spacing partitions 8, 9 separate the tubular members from each other. Arcuate spaces 10 are disposed intermediate of the partitions or bridges 8, and intermediate of the partitions or bridges 9 are arcuate spaces 11. The tubular member 4 is the outermost of the three tubular members and is provided externally with annular sloping surfaces 12, 13, the latter being undercut at 14 as shown more particularly in Fig. 2. An annular head 15 is provided for the purpose of supporting the weight of the insulating tube and such conductors as may be in turn supported by it. All parts of the insulating tube are integral.

My invention is used as follows:—The insulating tube is mounted in position by being merely inserted within a suitable aperture. A conductor, such as a cable or a large wire, may now be threaded through the cylindrical space 7 of the tubular member 6. In this case the spaces 10, 11 ordinarily serve as air spaces and improve the insulating qualities of the device. If desired, however, comparatively small conductors, such as wires, may be threaded separately through the spaces 10, 11, and thus not only separated from other conductors but thoroughly insulated as well. In case several wires are separately insulated each with its own covering, they may be threaded through any one or more of the spaces 10, 11.

In the construction described, the conformity of the parts is such as to afford a maximum of mechanical strength with a minimum of material. The insulating tube as a whole may be considered as having a cellular texture. It should be noted that the distance from the cylindrical aperture 7 to the outer circumference of the insulator is considerable as compared with the quantity of material employed in the insulator. It will also be noted that the bridges 9 are staggered relatively to some of the bridges 8, and that the circumferential widths of the spaces 10 are not very different from those of the spaces 11. This insures conformity of cellular structure.

If the insulating tube be subjected to a

crushing strain either in the general direction of its longest axis or across the direction of such axis, the strains are so distributed that the insulating tube is not readily broken.

5 The under-cuts 14 tend to prevent the creeping of moisture over the outer surface of the insulator. In case the surfaces 12, 13, should become wet by the leakage of moisture, or otherwise, the under-cut portions 13 are so disposed as not to be within the path of the moisture, the result being that the insulating tube will always present a number of comparatively dry annular spaces. It will be noted that the under-cuts 14 are found only 10 upon the upper half of the insulator as shown in Fig. 2, the material below the annular surfaces 12 being solid. The purpose of this arrangement is to increase the strength of the insulator at its lower end, the principle being 15 that the upper middle part of the insulator is usually protected within the aperture, and is, if practicable, a little more secure than the lower portion.

20 The insulating tube is provided at one of its ends immediately adjacent to the annular head 15 with a boss 16 provided with an annular channel 17 whereby it is encircled. This boss is provided with ordinals 18, 19, whereby the various arcuate spaces 10 may 25 be designated and conveniently located so as to be distinguishable from each other. This arrangement is of special value in cases where wires are threaded through the arcuate spaces 10, 11, and where it is desired to keep 30 several insulating tubes in such registry with each other that the wires pursue practically the same course throughout all of the connected insulating tubes. Each of the spaces or compartments being located numerically 35 enables the engineer to locate any particular cable, wire, or wires, should it become necessary to repair or remove them, besides enabling him to keep a record regarding the 40 number of compartments still available in case they should have been left unused when 45 the tubes were just installed. Each insulating tube is also provided with an annular depression 20 merging into an annular channel 21, these parts upon one tubular insulator being arranged to register with the boss 16 and the channel 17 of the next successive 50 insulating tube as shown in Fig. 2. When 55 two of the insulating tubes are thus fitted together a plastic material may be filled into the channels 20, 21, which are now merged together and constitute a channel having a cylindrical cross section as shown in said figure. The member 22 of this figure represents an annular holding of insulating material. Each insulating tube is provided with an aperture 23 for permitting the introduction of the material thus used as a 60 filling.

It is a known principle that throughout all bodies having the form of a cylinder

or of a plurality of concentric cylinders are of comparatively great strength. It is also true that a given amount of material possesses a maximum of torsional and tensile strength if made into the form of a cylinder. It is 70 upon this account that I incorporate in my tube a plurality of tubular members. If, however, these tubular members were loose relatively to each other, or were not connected together by any sort of positive members 75 or connections, their strength would not be as great as if properly connected and their rigidity as a unit would be impaired. Besides it would be less effective for insulating purposes. It is for this reason that I employ the bridges 8, 9 and also make the several parts integral. I do not limit myself, however, to the precise construction shown. Neither do I limit myself to the exact 80 conformity of any part of the tube, nor to any particular material out of which the latter is constructed. When desired for insulating purposes I prefer to use the material known in this art as "electrose", but hard rubber, 85 porcelain, glass, or in fact almost any other 90 suitable insulating material may be employed. I do not in every instance limit myself to the use of insulating material, nor do I restrict the use of the device to purposes of 95 insulation.

Having thus described my invention, I claim as new and desire to secure by Letters Patent:

1. A tube of insulating material, comprising a plurality of cylindrical members disposed concentrically and connected together by spacing partitions, one of said spacing partitions, used for connecting together two of said tubes, being staggered relatively to another of said partitions used for connecting together two other tubes.

2. A tube of insulating material, comprising a plurality of cylindrical members disposed concentrically and connected together by spacing partitions, one of said spacing partitions being staggered relatively to another of said spacing partitions, and a plurality of other spacing partitions disposed one nearer the center than another and in direct radial alignment relatively to said center.

3. A tube of insulating material, comprising a plurality of cylindrical members disposed concentrically and connected together by spacing partitions, one of said spacing partitions being staggered relatively to another, said tube being further provided with ordinals arranged in different groups, the ordinals of one group being staggered relatively to those of the other group for the purpose of indicating the relative location of spaces intermediate said partitions.

4. The combination of a plurality of tubes, each provided adjacent to one of its ends with a cylindrical portion encircled by an

annular channel, each tube being further provided at its opposite end with a cylindrical portion having an annular channel internally thereof, the annular channel of one end of said tube mating the annular channel of the opposite end of the next successive tube, a member disposed partly within the annular channel of one tube and partly in the annular channel of the other tube for the purpose

of holding said tubes together and being alone sufficient for this purpose.

In testimony whereof I have signed my name to this specification in the presence of two subscribing witnesses.

LOUIS STEINBERGER.
